ELECTRON TUBE SYSTEM

Sidney Y. White, New York, N. Y., assignor, by
mesne assignments, to Radio Corporation of
America, New York, N. Y., a corporation of
Delaware

Application May 6, 1930, Serial No. 450,070

11 Claims. (Cl. 179—171)

My present invention relates to electron tube systems, and more particularly to cascaded electron tube systems.

In direct coupled cascaded tube systems, or in resistance coupled cascaded tube systems, it is frequently difficult to operate a pair of output tubes connected in so-called push-pull arrangement from a single input tube. Since these two types of systems have become of particular practical importance, I have developed an output system particularly suitable to them as well as to transformer coupled systems that hereinafter is termed a cascade output system.

An object of my invention is a cascade output system functioning within a transformer coupled, direct coupled, or resistance coupled electron tube system with the advantages of a push-pull output system insofar as signal currents are concerned, and without the difficulties inherent 20 in the push-pull output system when employed in conjunction with a direct coupled tube system.

Other objects of my invention will become apparent as the description of my invention is developed with reference to the accompanying 25 drawings in which

Fig. 1 diagrammatically illustrates my cascade output system employed with a transformer input system;

Fig. 2 diagrammatically illustrates my cascade output system employed with a direct coupled tube system, disclosed in my copending applications Serial Number 381,754, filed July 29, 1929 and Serial Number 448,839 filed May 1, 1930.

Fig. 3 diagrammatically illustrates a modification of the cascade output system of Fig. 1 when employed with the direct coupled tube system of Fig. 2.

Fig. 4 diagrammatically illustrates a modification of the circuit arrangement of Fig. 3;

Fig. 5 diagrammatically illustrates a modification of the cascade output system disclosed in Figs. 1 and 2.

Fig. 6 diagrammatically illustrates a modification of the circuit arrangement of Fig. 5.

Fig. 7 diagrammatically illustrates a modification of the circuit arrangement of Fig. 4, and

Fig. 8 diagrammatically illustrates a modification of the circuit arrangement of Fig. 7.

In commercial radio receivers and amplifiers 50 of the present, employing an electrodynamic speaker, the feature of the energization of the field coil of such a speaker without additional drain upon the filter system of the usual energizing source presents a serious problem. In the cascade output system to be hereinafter described I show the solution of this problem as an incidental feature thereof, but it is to be understood that the substitution of an impedance element in the place of the speaker field coil may be made without departing from the spirit of my

invention as defined in the claims appended here-to except wherein this feature is specifically included in certain of those claims. In all figures the coil designated SFC may, therefore, be the field coil of the translating device or represent 65 any other suitable impedance element.

Referring to Fig. 1, R/T designates a full wave rectifier tube energized from a source of alternating current AC through a power transformer PT. The negative or grounded terminal G and the positive terminal P of the rectifier system are shunted by a pair of filter condensers FC₁ and FC₂ with a series filter choke coil FC_h connected in the manner shown.

The terminal P of the rectifier system is connected through the filter choke coil FC_h to the center tap of the primary of an output transformer OT, the secondary of the transformer being connected to a loud speaker LS, preferably of the electrodynamic type, the terminals of the primary of the transformer OT being connected to the anodes of tubes VT₂ and VT'₂. The cathodes of tubes VT₂ and VT'₂ are connected in parallel and energized from a heating current transformer HT₂ provided with a center-tap CT₂ which is connected to the negative terminal G of the rectifier system through the field coil SFC which is preferably that of the speaker LS and a resistance R, in this instance the resistance R being so chosen that the potential difference between the points CT₂ and G is equal to the normal grid bias of tubes VT₂ and VT'₂. 75 80 85

The grid of tube VT₂ is connected to the terminal G through the secondary of an input transformer IT. The grid of tube VT'₂ is connected to the terminal G through a coupling resistance CR' and to the plate of tube VT₂ through a coupling resistance CR'' and a coupling condenser CC. 90 95

The operation of this system is as follows: The space current of tubes VT₂ and VT'₂ flowing through the speaker field coil SFC and the resistance R energizes the speaker field and, due to the potentials developed therein, the grids of tubes VT₂ and VT'₂ are maintained at the proper 100 105 average potential with respect to the cathodes thereof.

Assuming a signal current energizing the transformer IT, the signal currents are amplified by the tube VT₂ with the resultant amplified signals passing through parallel paths, one of which is the section 1 of the primary of transformer OT and the other path through the condenser CC and the coupling resistances CR'' and CR'. 110

The signal currents at the grid of tube VT'₂ connected to this latter path are in opposing phase with the signal currents in the input circuit of VT₂ and, if the coupling resistance CR' is so chosen with respect to the coupling resistance CR'' that there are impressed between the grid 115 120

and cathode of tube VT_2' signal current potentials from the amplified output of tube VT_2 equal to those developed between the cathode and grid of tube VT_2 , current variations in the sections 1 and 2 will be equal and additive in effect in the secondary of the transformer OT.

Such a cascade output system possesses all of the favorable characteristics of a push-pull output system with no need for by-passing the bias 10 arm comprising the resistance R and the field coil SFC.

The system possesses the further feature that when the value of the resistance CR' approaches the normal input impedance of the tube VT_2' , the impedance of the connection CC, CR'' , CR' is of the order of 20 to 50 times that of the impedance of the section 1 of the output transformer OT, so that the substantially full output of tubes VT_2 and VT_2' can be supplied to the output 20 transformer OT, each tube being energized with signal current potentials of the order of that developed across the secondary of transformer IT, whereas in a push-pull system the potential in the secondary of the push-pull input transformer 25 is divided into two equal parts. For this reason and others, with a given signal input voltage in the cascade output system described the overall amplifying ability is considerably greater than that of a push-pull connected system actuated 30 by the same signal input voltage, I having actually constructed systems having amplification factors of from 7 to 32 times that of a conventionally push-pull connected equivalent system.

Referring to Fig. 2, I have indicated the rectifier and filter system of Fig. 1 merely by a symbol labeled "Current Source", and have modified the cascade output system of Fig. 1 to adapt the same for use in a direct coupled cascaded electron tube system.

40 The terminal P of the source SF is connected to the center tap of the primary of the output transformer OT, the terminals of which transformer are connected to the anodes of tubes VT_2 and VT_2' . The cathodes of the tubes VT_2 and VT_2' are connected in the manner shown in Fig. 1, but for simplicity I have omitted the showing of the heating current transformer HT_2 and have provided the cathodes with center taps CT_2 and CT_2' connected to the negative terminal G of the 45 source SF through the field coil SFC, preferably that of the loud speaker or similar translating device, and resistance R, of higher value than that of resistance R in Fig. 1, the source having also a higher potential of output.

50 The grid of tube VT_2 is returned to the terminal G through the anode-to-cathode path of a four element tube VT_1 and a stabilizing resistance SR series related therewith. The grid of tube VT_1 is returned to the point A of proper 55 potential on the resistance R through the signal input provided with a signal current condenser SC. The signal input may be any source of variable voltage that it is desired to amplify.

60 The screen grid of tube VT_1 is connected to the point B on the resistance R of proper potential, and tube VT_1 is provided with a hum-bucking condenser HBC connected between the cathode and a selected point D on the resistance R. The 65 common connection between the plate of tube VT_1 and the grid of tube VT_2 is returned through a coupling resistance CR to a point between two high resistances R' and R'' connected between the terminal P and the center tap CT_2 of the 70 cathode of tube VT_2 , the additional load placed 75

on the filter system being only that of the order of the small space current of tube VT_1 .

The functions of these various connections between tubes VT_1 and VT_2 are described in detail in my copending applications hereinbefore referred to and in papers published by myself and Edward H. Loftin in the February, March and April 1930 issues of Radio News, Experimenter Publications, Inc., Jamaica, N. Y.

In this arrangement of Fig. 2, the connection of the plate of tube VT_2 to the grid of tube VT_2' through the coupling condenser CC and the coupling resistances CR'' and CR' is returned to the point E on the resistance R of the proper potential to maintain the normal bias voltage on the grid of tube VT_2' with respect to the cathode thereof.

The operation of this arrangement with respect to signal currents is as follows: Signal current voltages introduced at the signal input are amplified by the tubes VT_1 and VT_2 in the normal manner of a direct coupled tube system, the output of tube VT_2 passing through parallel paths, one of which is the section 1 of the primary of output transformer OT and the other of which is through the condenser CC and the coupling resistances CR'' and CR' .

Analogous to Fig. 1, the signal currents at the grids of the two tubes VT_2 and VT_2' are in opposing phase, and if the coupling resistance CR' is so chosen with respect to the coupling resistance CR'' that there are impressed between the grid and cathode of tube VT_2' signal current potentials equal to those developed between the grid and cathode of tube VT_2 , current variations in the sections 1 and 2 of the output transformer OT will be equal and additive in effect in the secondary of the transformer OT.

Such a cascade output system possesses all of the favorable advantages of the circuit of Fig. 1 with the added feature of uniform with frequency amplification of the input signal currents inherent in direct coupled tube systems when compared with the non-uniform transfer of signal current energy through a transformer system indicated at IT in Fig. 1.

This cascade output system likewise has an amplification factor several times that of a direct coupled push-pull system of the type disclosed by Paul P. Stoutenburgh in application Serial Number 443,294, filed April 11, 1930, with the use of a like number of tubes for the same reasons as set forth hereinbefore for the high amplification factor of the system disclosed in Fig. 1 when compared with the push-pull transformer coupled systems.

In Fig. 3, I have shown a modification of the cascade output systems of Figs. 1 and 2 wherein I have embodied a feature of direct coupling between tubes VT_2 and VT_2' by eliminating the coupling condenser CC of Fig. 2 and connecting the coupling resistance CR'' directly to the anode of tube VT_2 and the coupling resistance CR' to the terminal G of the source SF.

An analysis of this circuit arrangement shows that the coupling resistances CR'' and CR' are series connected between the plate of tube VT_2 and the terminal G forming a direct current potentiometer across the source, the bias of tube VT_2' being determined by the ratio of resistances CR'' and CR' .

With respect to the signal current potentials, this circuit arrangement is the same as previously described with reference to Figs. 1 and 2 with

the additional feature that the condenser CC has been eliminated, which eliminates any frequency selective characteristic of the cascade output system.

5 In Fig. 4, I have shown a separate resistance R_1 and a coil SFC for the tube VT_2 , the center taps CT_2 and CT'_2 being connected together through a condenser SC_2 of low impedance to signal currents. Otherwise the circuit arrangement is identical with that of Fig. 3. The provision of separate resistances R and R_1 for the tubes VT_2 and VT'_2 limits the reaction of the stabilizing system including resistance SR and connection of the grid of VT_1 to point A to potentials developed from the space current of tube VT_2 only, so that if anything within the system relating to tube VT'_2 should fail the tubes VT_1 and VT_2 carry on as a simple direct coupled tube system.

20 In Fig. 5, I have shown modifications of the cascaded output systems of Figs. 1 and 2 modified in that I have returned the coupling resistance CR'' to the center tap CT_2 through a coupling condenser CC' , and have maintained the grid of tube VT'_2 at the same average potential as the grid of tube VT_2 , but isolated therefrom with respect to signal current fluctuations, by connecting between the two grids an isolating resistance IR .

25 In Fig. 6, I have shown a modification of the circuit arrangement of Fig. 5 in that I have connected the isolating resistance IR between the grid of tube VT_2 and the low potential terminal of the coupling resistance CR'' . In this manner I have been able to effectively isolate the grid of tube VT'_2 from the fluctuations at the grid of tube VT_2 since the combination of the condenser CC' in conjunction with the resistance IR acts as a resistance-condenser filter system.

30 In Fig. 7, I have shown a modification of the signal current coupling means of Fig. 6 between the tubes VT_2 and VT'_2 . Herein, I have shown the coupling resistances CR'' and CR' series connected between the plates of tubes VT_2 and VT'_2 , or across the terminals of the output transformer OT . When so connected along the resistances CR'' and CR' there are developed signal current potentials of similar phase to those along the sections 1 and 2 of the primary of the output transformer OT . Therefore the resistances CR'' and CR' should be so chosen that their junction point is at the same signal current potential with respect to the current flowing in the output circuit of tube VT_2 as the junction point between these same resistances is chosen with respect to the signal currents flowing in the output circuit of the tube VT'_2 of the preceding figures. These signal current potentials are transmitted to the grid of tube VT'_2 through a coupling condenser CC , the grid bias of the tube VT'_2 being determined by the isolating resistance IR as in the previous figures.

35 In Fig. 8, I have shown a modification of the system of Fig. 7 in that I have shown the grid of tube VT'_2 directly connected to the junction between the resistances CR'' and CR' , and to the tap on the isolating resistance IR which is connected in shunt to the coil SFC, by which the bias on the grid of tube VT'_2 is determined, the resistances CR'' , CR' , IR , and R functioning as a potentiometer across the terminals P and G of the source.

40 While I have described my invention as embodied in several specific circuit arrangements, it

is to be understood that various modifications and combinations of the features thereof may be made without departing from the spirit of my invention as defined in the claims appended hereto.

Having thus described my invention, what I claim is:

1. In a cascade output system, the combination of a source of power, an output transformer having a tapped primary, the tap of which is connected to one terminal of said source, a pair of electron tubes the anodes of which are connected to the terminals of said primary, potential developing elements connecting the cathodes of said tubes to the other terminal of said source, a signal input system for one of said tubes, comprising a third electron tube the plate circuit of which is directly coupled to the grid circuit of said one tube, an auxiliary signal output circuit for said one tube, means coupling the grid of the other tube of said pair to said auxiliary output circuit whereby the signal current variations in the primary of said output transformer due to the varying impedance of each of said tubes are predetermined, and means for maintaining the grids of each of said tubes at the proper bias potential with respect to the cathodes thereof. 85

2. In a cascade output system, the combination of a source of power, an output transformer having a tapped primary, the tap of which is connected to one terminal of said source, a pair of electron tubes the anodes of which are connected to the terminals of said primary, potential developing elements connecting the cathodes of said tubes to the other terminal of said source, a signal input system for one of said tubes, comprising a third electron tube the plate circuit of which is directly coupled to the grid circuit of said one tube, an auxiliary signal output circuit for said one tube, means coupling the grid of the other tube of said pair to said auxiliary output circuit whereby the signal current variations in the primary of said output transformer due to the varying impedance of each of said tubes are substantially equal, and means for maintaining the grids of each of said tubes at the proper bias potential with respect to the cathodes thereof. 100

3. In a cascade output system, the combination of a source of power, an output transformer having a tapped primary, the tap of which is connected to one terminal of said source, a pair of electron tubes the anodes of which are connected to the terminals of said primary, potential developing elements connecting the cathodes of said tubes to the other terminal of said source, a signal input system for one of said tubes, an auxiliary signal output circuit for said one tube, means coupling the grid of the other tube of said pair to said auxiliary output circuit whereby the signal current variations in the primary of said output transformer due to the varying impedance of each of said tubes are predetermined, and means for stabilizing the average plate current of at least one of said pair of tubes. 115

4. In a cascade output system, the combination of a source of power, an output transformer having a tapped primary, the tap of which is connected to one terminal of said source, a pair of electron tubes the anodes of which are connected to the terminals of said primary, potential developing elements connecting the cathodes of said tubes to the other terminal of said source, a signal input system for one of said tubes, an auxiliary signal output circuit for said one tube, means coupling the grid of the other tube of said pair to said auxiliary output circuit whereby the 125

signal current variations in the primary of said output transformer due to the varying impedance of each of said tubes are predetermined, and means for stabilizing the average plate current of each of said pair of tubes.

5. In a cascade output system, the combination of a source of power, an output transformer having a tapped primary, the tap of which is connected to one terminal of said source, a pair 10 of electron tubes the anodes of which are connected to the terminals of said primary, potential developing elements connecting the cathodes of said tubes to the other terminal of said source, a signal input system for one of said tubes, comprising a third electron tube the plate circuit of which is directly coupled to the grid circuit of said one tube, an auxiliary signal output circuit for said one tube, means coupling the grid of the other tube of said pair to said auxiliary output circuit whereby the signal current variations in the primary of said output transformer due to the varying impedance of each of said tubes are predetermined, and means energized 15 from the space current flow of said third electron tube for maintaining the grids of each of said tubes at the proper bias potential with respect to the cathodes thereof.

6. In a cascade output system, the combination of a source of power, an output transformer having a tapped primary, the tap of which is connected to one terminal of said source, a pair 30 of electron tubes the anodes of which are connected to the terminals of said primary, potential developing elements connecting the cathodes of said tubes to the other terminal of said source, a signal input system for one of said tubes, an auxiliary signal output circuit for said one tube, means coupling the grid of the other tube of said pair to said auxiliary output circuit whereby the signal current variations in the primary of 35 said output transformer due to the varying impedance of each of said tubes are predetermined, and means including a third electron tube for stabilizing the average plate current of at least 40 one of said pair of tubes.

7. In a cascade output system, the combination of a source of power, an output transformer having a tapped primary, the tap of which is connected to one terminal of said source, a pair 50 of electron tubes the anodes of which are connected to the terminals of said primary, potential developing elements connecting the cathodes of said tubes to the other terminal of said source, a signal input system for one of said tubes comprising 55 a third electron tube the plate circuit of which is directly coupled to the grid circuit of said one tube, an auxiliary signal output circuit for said one tube, means coupling the grid of the other tube of said pair to said auxiliary output circuit whereby the signal current variations in the primary of 60 said output transformer due to the varying impedance of each of said tubes are predetermined, and means for stabilizing the average plate current of at least one of said 65 pair of tubes.

8. In a cascade output system, the combination of a source of power, an output transformer having a tapped primary, the tap of which is connected to one terminal of said source, a pair 70 of electron tubes the anodes of which are connected to the terminals of said primary, potential developing elements connecting the cathodes of said tubes to the other terminal of said source,

a signal input system for one of said tubes comprising a third electron tube the plate circuit of which is directly coupled to the grid circuit of said one tube, an auxiliary signal output circuit for said one tube, means coupling the grid of the other tube of said pair to said auxiliary output circuit whereby the signal current variations in the primary of said output transformer due to the varying impedance of each of said tubes are substantially equal, and means for stabilizing 80 the average plate current of at least one of said pair of tubes.

9. In a cascade output system, the combination of a source of power, an output transformer having a tapped primary, the tap of which is connected to one terminal of said source, a pair of 85 electron tubes the anodes of which are connected to the terminals of said primary, potential developing elements connecting the cathodes of said tubes to the other terminal of said source, a signal input system for one of said tubes comprising a third electron tube, the plate circuit of which is directly coupled to the grid circuit of said one tube, an auxiliary signal output circuit for said one tube, means coupling the grid of the other tube of said pair to said auxiliary output circuit whereby the signal current variations in the primary of said output transformer due to the varying impedance of each of said tubes are predetermined, and means for stabilizing 95 the average plate current of at least one of said pair of tubes.

10. In a cascade output system, the combination of a source of power, an output transformer having a tapped primary, the tap of which is connected to one terminal of said source, a pair 100 of electron tubes the anodes of which are connected to the terminals of said primary, potential developing elements connecting the cathodes of said tubes to the other terminal of said source, a signal input system for one of said tubes comprising a third electron tube, the plate circuit of which is directly coupled to the grid circuit of said one tube, an auxiliary signal output circuit for said one tube, means coupling the grid of the other tube of said pair to said auxiliary output circuit whereby the signal current variations in the primary of said output transformer due to the varying impedance of each of said tubes are predetermined, and means for stabilizing 105 the average plate current of each of said pair of tubes.

11. In a cascade output system, the combination of a source of power, an output transformer having a tapped primary, the tap of which is connected to one terminal of said source, a pair 110 of electron tubes the anodes of which are connected to the terminals of said primary, potential developing elements connecting the cathodes of said tubes to the other terminal of said source, a signal input system for one of said tubes comprising a third electron tube, the plate circuit of which is directly coupled to the grid circuit of said one tube, an auxiliary signal output circuit for said one tube, means coupling the grid of the other tube of said pair to said auxiliary output circuit whereby the signal current variations in the primary of said output transformer due to the varying impedance of each of said tubes are predetermined, and means for stabilizing 115 the average plate current of each of said pair of tubes.

12. In an electric system including two amplifying control-electrode discharge tubes having 120 their output impedances arranged for push-pull operation, and means and connections for energizing electrodes of said tubes, the combination of a signal input system for impressing signals on one of said two tubes, an auxiliary impedance 125 connected to the output of said one tube for diverting therefrom signal energy of the order of that impressed on the input thereof, means for impressing from said auxiliary impedance on the input of the other of said two tubes signal energy 130 equal in magnitude but opposite in phase to that impressed on the input of said one tube, and means for maintaining the control electrodes of both said tubes at desired average potentials with 135 respect to their associated cathodes.

SIDNEY Y. WHITE.
